CLAIM

The ornamental design for a hands free animal leash, as shown and described.

DESCRIPTION

FIG. 1 is a front elevational view of a hands free animal leash showing my new design, the broken lines are for illustrative purposes only forming no part of the claimed design; and,

FIG. 2 is a front perspective view thereof, the collar, leash and belt are shown detached for clarity of disclosure. The leash portion of the claimed design is understood to be of indeterminate length.
